COMBINED VALET STAND AND SEAT

Harold Gleitsman, New Rochelle, and Carl Fuerst, Bronx,
N.Y., assignors to Gleitsman's, Inc., Long Island City,
N.Y., a corporation of New York

Filed Dec. 29, 1961, Ser. No. 68,123

Term of patent 14 years

(Cl. D33—3)

FIG. 2

FIG. 5

FIG. 3

FIG. 1

FIG. 1 is a front perspective view, on an enlarged scale, of the combined valet stand and seat showing our new design;

FIG. 2 is a top plan view thereof;

FIG. 3 is a side elevational view thereof;

FIG. 4 is a rear view thereof; and

FIG. 5 is a bottom view thereof.

We claim:

The ornamental design for a combined valet stand and seat, substantially as shown.
